US0D1029904S

(12) **United States Design Patent** (10) Patent No.: **US D1,029,904 S**
(45) Date of Patent: ** Jun. 4, 2024

(54) **CAMERA HOUSING**

(71) Applicant: **GoPro, Inc.**, San Mateo, CA (US)

(72) Inventors: **Jordan Todd**, Piedmont, CA (US);
Matthew David Thomas, Castro
Valley, CA (US); **Daniel J. Coster**,
Oakura (NZ); **Bessy Liang**, San Jose,
CA (US); **Huy Phuong Nguyen**,
Alpine, UT (US)

(73) Assignee: **GoPro, Inc.**, San Mateo, CA (US)

(**) Term: **15 Years**

(21) Appl. No.: **29/905,199**

(22) Filed: **Oct. 17, 2023**

Related U.S. Application Data

(60) Continuation of application No. 29/847,856, filed on Jul. 28, 2022, which is a continuation of application No. 29/835,094, filed on Apr. 15, 2022, now Pat. No. Des. 963,023, which is a division of application No. 29/817,137, filed on Nov. 29, 2021, now Pat. No. Des. 954,132, which is a division of application No. 29/744,859, filed on Jul. 31, 2020, now Pat. No. Des. 963,016.

(57) CLAIM

The ornamental design for a camera housing, as shown and described.

DESCRIPTION

FIG. 1 is a bottom, front and left side perspective view of a camera housing showing our new design;

FIG. 2 is a top, rear and right side perspective view thereof;

FIG. 3 is a front view thereof;

FIG. 4 is a rear view thereof;

FIG. 5 is a top view thereof;

FIG. 6 is a bottom view thereof;

FIG. 7 is a right view thereof; and,

FIG. 8 is a left view thereof.

The broken lines depict portions of the camera housing in which the design is embodied that form no part of the claimed design.
